United States Patent

Des. 236,167
Patented July 29, 1975

236,167

COMBINED HAIR DETANGLER AND HOLDER THEREFOR

Theodore G. Daher, Stratford, Conn., assignor to
General Electric Company

Filed Oct. 1, 1973, Ser. No. 402,034

Term of patent 3½ years

Int. Cl. D28—03

U.S. Cl. D86—8

FIG. 1.

FIG. 3

FIG. 4.

FIG. 2.

FIG. 5.

FIG. 6.

FIG. 7.

FIG. 8.

FIG. 9.

FIG. 10.

FIG. 11.

FIG. 1 is a perspective view of a combined hair detangler and holder therefor showing my new design;

FIG. 2 is a perspective view of the holder alone, it being understood that the scroll decoration which is continuous around the base is shown partially in FIGS. 2 and 4 for ease of illustration;

FIG. 3 is a side elevational view thereof;

FIG. 4 is a top plan view thereof;

FIG. 5 is a bottom plan view thereof;

FIG. 6 is a perspective view of the detangler alone;

FIG. 7 is a top plan view thereof;

FIG. 8 is a bottom plan view thereof;

FIG. 9 is a side elevational view;

FIG. 10 is a handle end elevational view; and

FIG. 11 is a comb end elevational view.

I claim:

The ornamental design for a combined hair detangler and holder therefor, substantially as shown and described.
